UNITED STATES PATENT OFFICE.

CHARLES STICHEL, OF SAN FRANCISCO, CALIFORNIA, ASSIGNOR TO PACIFIC BOX FACTORY, INC., OF SAN FRANCISCO, CALIFORNIA, A CORPORATION OF CALIFORNIA.

FEEDING-TABLE.

1,271,959.

Specification of Letters Patent. Patented July 9, 1918.

Application filed July 18, 1917. Serial No. 181,244.

To all whom it may concern:

Be it known that I, CHARLES STICHEL, a citizen of the United States, residing in the city and county of San Francisco and State 5 of California, have invented new and useful Improvements in Feeding-Tables, of which the following is a specification.

This invention relates to a feeding table for re-cut band saws.

10 The object of the present invention is to provide a simple, compact, easily operated and adjustable machine for re-cutting box ends of varying sizes and thickness, and in conjunction therewith to provide means for 15 automatically feeding the ends in successive order through the re-cutting saw. Further objects will hereinafter appear.

20 The invention consists of the parts and the construction and combination of parts 25 as hereinafter more fully described and claimed, having reference to the accompanying drawings, in which—

Figure 1 is a plan view of the machine.

Fig. 2 is a detail side elevation of the top 25 guide, the view being taken on line 2—2 of Fig. 1.

Fig. 3 is a detail side elevation of the idler sprocket 14.

Fig. 4 is a detail view of the slidably 30 mounted adjusting block 15.

Fig. 5 is a vertical cross-section on line 5—5 of Fig. 1.

Fig. 6 is a cross-section on line 6—6 of Fig. 5.

35 Fig. 7 is a detail view of the friction clutch and sprocket by which the primary feeding chain is driven.

Fig. 8 is a similar view of the friction 40 clutch and sprocket through which the secondary feeding chain is driven.

Fig. 9 is a plan view of the adjustable frame in which one of the idling sprocket supporting the secondary feeding chain is supported.

45 Fig. 10 is a plan view in section of the feeding rollers through which the blocks pass before they engage the saw.

Referring to the drawings in detail, particularly Fig. 1, A indicates a feeding table 50 in one end of which is journaled a driving shaft 2. This shaft is supported on top of the table while the secondary driving shaft 3 is journaled below the table. Power is transmitted to the shaft 2 through a pulley 4 and a clutch 5 which may be thrown into

or out of engagement by a shifting lever 6. Power is in turn transmitted to the secondary driving shaft through a chain drive 7. Mounted on one end of the secondary shaft is a friction clutch 8 which is normally held 60 in driving engagement by spring 9 and carried by said friction clutch is a sprocket gear 10 which carries an endless feeding chain 11. This chain runs on a plane parallel with the table surface and is provided with a 65 plurality of feeding lugs 12 which pass through a slot 13 formed in the table.

Mounted on one side of the chain 11 which will hereinafter be known as the primary feed, is a vertically disposed guiding plate 70 16. The forward end of this plate is turned at right angles as at 17, and the plate as a whole is adapted to be adjusted to and away from the primary feed and also to and away from a main guiding plate 18. The adjustment of the guiding plate consisting of the sections 16 and 17 is accomplished in the following manner:

Slidably mounted in slots 19 formed on the sides of the table is a pair of adjusting blocks 15. Extending through each block in a direction parallel with the plate 16 is a screw shaft 20. Turning movement of this shaft by means of a hand-wheel 21 causes the blocks to move endwise and thereby permits the plate section 17 to be moved to or away from the main guide 18. Extending through each block 15 at right angles to the screw shaft 17 is a screw shaft 22, the inner ends of which are journaled in bearings 23 85 formed on the rear side of plate 16. Secured on the inner end of each screw shaft 22 is a sprocket gear 14 and passing over said sprockets is an endless chain 24. Turning movement of one of the shafts 22 by 90 means of a hand-wheel 25 transmits movement through the chain 24 and the sprockets to turn the opposite screw shaft 22. This causes the plate section 16 to move to or away from the primary feed and therefore 95 permits box ends or blocks such as shown at 26 to be adjusted endwise with relation to the primary feed.

The main guiding plate 18 is carried by a pair of brackets 27 which are slidably 105 mounted in dove-tailed grooves 28, see Figs. 5 and 6, formed in a guide rail 29, secured on top of the table. The plate 18 together with the frames 27 are adapted to be moved in unison by a screw adjustment comprising 110

ing a shaft 30, a hand-wheel 31, a pair of screw shafts 32 and two pairs of bevel gears 33. That is, turning movement of shaft 30 by means of the hand-wheel 31 transmits movement through each set of bevel gears 33 to turn the screw shafts 32, and as these are journaled at one end in bearings 34 carried by the guide rails 29 and extend through lugs 35 carried by the frames 27, it can readily be seen that endwise movement is imparted to permit the frames 27 carrying the main guiding plate 18 to be adjusted with relation to the guiding plate 17. The necessity of adjustably mounting the plates 17—18 is due to the fact that the band saw shown at 36 in Fig. 10, remains in a fixed position, and it is also due to the fact that the blocks 26 to be re-cut often vary in thickness. The center of the block 26 should be in exact alinement with the saw, hence the necessity of adjusting both plates. The blocks when placed upon the table against the guide plate 16 are moved in the direction of arrow *a* by means of the primary feed 13. Their forward movement is however stopped by the guiding plate 18 and they are here removed one by one in successive order by a secondary feed comprising an endless sprocket chain 38 carrying lugs 39 engageable with each individual block. The chain 38 is carried by a pair of idlers 40 journaled on the rear side of the main guiding block 18 and also by a driving sprocket 41 which is secured upon a vertically disposed shaft 42 suitably journaled in the table and driven from the secondary shaft 3 through a pair of bevel gears 43, see Fig. 8. A friction clutch similar to the clutch 8 previously described is here also employed for purposes to be hereinafter described.

In view of the fact that the idlers 40 are carried by the main plate 18, it can readily be seen that it is necessary to take up slack in the chain 38 when the position of plate 18 is changed. This is due to the fact that the shaft 42 carrying the driving sprocket 41 remains stationary. The outer end of shaft 30 is therefore screw-threaded as at 44 and extends through lugs 45 formed on the frame, which is adjustably mounted on the rear side of the plate 18. Turning movement of shaft 30 when the plate 18 is adjusted will therefore simultaneously move the adjustable frame carrying the idler 40, thereby taking up or giving out slack to chain 38 when adjustment is being made.

The plate 18 also serves as a support for a top guide generally indicated at 50; this guide being adjustably mounted upon a pair of rods 51 and it is adapted to be secured in any adjusted position by a pair of set screws 52.

In operation it is only necessary to place the box ends or blocks 26 in the position

shown against the guide 16. Movement of the primary feeding chain 13 in the direction shown causes the lugs carried thereby to move the stack of blocks forward against the plate 18. They are here in turn moved one by one by the lugs 39 secured on the secondary feeding chain 38 and will therefore pass under the top guide 50 and between a pair of feeding rollers 60, see Figs. 1 and 10, directly to the saw 36 where they are re-cut to any thickness desired, and discharged in any suitable manner. The necessity of providing a friction drive in connection with the primary and secondary feed is first to permit the stack of blocks 26 to remain stationary while the forward block is being removed, and to again automatically move the stack up against the plate 18 to permit the next forward block to be removed. Similarly, by providing a friction drive on the secondary feed it is possible to work the saw to its utmost. That is, if comparatively soft wood is being handled it can readily be seen that the blocks can be fed through the saw more rapidly than where harder woods are being handled. The friction drive therefore automatically feeds the blocks through the saw as rapidly as they can be handled.

The feeding mechanism as a whole is comparatively simple in construction and its operation is entirely automatic. The adjustments provided permit blocks practically of any size and thickness desired to be handled, and the friction drive employed increases the capacity of the saw, as it delivers the blocks as rapidly as the saw can handle same. The manual labor and the attention required is therefore comparatively small, and the cost of operation proportionately decreased.

The materials and finish of the several parts of the machine may be such as the experience and judgment of the manufacturer may dictate.

Having thus described my invention, what I claim and desire to secure by Letters Patent is—

1. In a feeding table, an adjustable guide plate having a chain receiving and guiding groove formed in its front face, an endless feed chain movable in the guiding groove, a fixed drive for the chain, and means for simultaneously adjusting the plates and maintaining the chain operatively taut during such adjustment of the plate.

2. In a feeding table, an adjustable guide plate, means for adjusting the plate including a nut and a co-operating and rotatable screw threaded member, sprockets journaled adjacent the ends of the guide plate, an endless chain passing about the sprockets, means for adjusting the mounting of one sprocket also including a nut and a co-operating and rotatable screw threaded member, means

connecting the latter to the first screw threaded member whereby on the adjustment of the plate the specified sprocket will also be adjusted to maintain an operative 5 tension on the chain, and a fixed drive sprocket relative to which the plate is movable.

3. In a feeding table, a main guide plate, a feeding chain passing longitudinally over 10 the plate, a second guide plate arranged at an angle in front of the main guide plate and having its inner end deflected to lie parallel with said main plate for defining a path therebetween, and a second feed chain 15 operating across the defined path for feeding material along the second guide plate against the main guide plate.

4. In a feeding table, a main guide plate, a feeding chain passing longitudinally over 20 the plate, a second guide plate arranged at an angle in front of the main guide plate and having its inner end deflected to lie parallel with said main plate for defining a path therebetween, a second feed chain 25 operating across the defined path for feeding material along the second guide plate against the main guide plate, screw threaded members carried by the second guide plate, fixed nuts through which the threaded 30 members operate for adjusting the second guide plate toward and from the second feed chain, and transmission means connecting the threaded members whereby rotation of one will effect rotation of the other for evenly adjusting the second guide plate. 35

5. In a feeding table, a main guide plate, a feeding chain passing longitudinally over 40

the plate, a second guide plate arranged at an angle in front of the main guide plate and having its inner end deflected to lie parallel with said main plate for defining a path therebetween, a second feed chain operating across the defined path for feeding material along the second guide plate against the main guide plate, screw threaded members 45 carried by the second guide plate, fixed nuts through which the threaded members operate for adjusting the second guide plate toward and from the second feed chain, transmission means connecting the threaded 50 members whereby rotation of one will effect rotation of the other for evenly adjusting the second guide plate, and a screw threaded member passing through both nuts for adjusting the deflected end of the second plate toward and from the main guide plate. 55

6. In a feeding table, a main guide plate, a feeding chain passing longitudinally over the plate, a second guide plate arranged at 60 an angle in front of the main guide plate and having its inner end deflected to lie parallel with said main plate for defining a path therebetween, and a top guide carried by one of the guide plates over the defined 65 path between the main guide plate and the deflected end of the second guide plate.

In testimony whereof I have hereunto set my hand in the presence of two subscribing witnesses.

CHARLES STICHEL.
